UNITED STATES PATENT OFFICE.

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY.

CURRENT-INDUCING DEVICE FOR RECORD-CONTROLLED MACHINES.

Application filed March 28, 1924. Serial No. 702,639.

The present invention is directed to improvements in record controlled machines and is more particularly directed to the provision of means for modifying the mode of 5 operation of these machines as heretofore constructed to the general end that the controlling circuits from the record card perforations to the magnet devices may be simplified by the omission of elements heretofore considered essential.

In the present invention provision is made for the omission of contacts and controlling resistances from the card and magnet circuits of such machines in order to lower the 15 cost of construction and to obviate the necessity of adjustment or replacement of such parts when the machines are in use.

Further objects of the present invention reside in the provision of electrical devices 20 for perforated record controlled machines which will permit the machines to operate at as high or higher operating speeds than heretofore without the attendant complication heretofore necessary to secure the desired fast circuit conditions.

In accordance with the present invention I provide means for supplying the card or brush and magnet circuits with direct current impulses which are timed to occur at the 30 time the record perforations pass under the brushes. In the event that there is a perforation under a given brush the direct current impulse will pass through the card and magnet circuit to the corresponding magnet 35 and energize the latter. If a perforation is absent, the direct current impulse will be interrupted by the card and the magnet will not be energized. Provision is made for supplying the current at high potential so 40 that the circuit operation will be extremely rapid.

In the drawings,

Fig. 1 shows a diagrammatic view of a perforated record controlled machine embodying the invention.

Fig. 2 is a detail view showing the timing contactor which is used in this machine.

In Fig. 1 of the drawings, 10 designates a stack of record cards which are fed by the usual upper and lower feed rolls 11, 12, past cooperating brushes 13 and contact blocks 14. The gearing for rotating the feed rolls is shown conventionally at 18. This gearing receives its drive from a shaft 20 which by a 55 belt and pulley connection is driven by the

tabulating motor TM. This gearing also drives the tabulator counter in the usual manner. A shaft 21 is driven in unison with the card feeding devices and makes one revolution per card cycle. This shaft carries 60 certain contact devices and contact cams as will be hereinafter described.

The card feeding section of the machine is provided with the usual card lever 22 which closes contacts 23 and supplementary contacts 24 when cards are passing under the brushes. To start the tabulator into operation the operator first closes main line switch 26 to the supply main. Thereafter start key 27 is depressed, which, upon the closure of the contacts, establishes a circuit from the line 28, tabulating motor TM, stop key 30, motor relay magnet 29 and back through wire 31 to source. The energization of the motor relay 29 establishes a holding circuit for the tabulating motor through the armature of motor relay magnet 29, line 32, through cam contacts 33 which are closed after the motor has rotated the parts and thence back through 70 31 to source. Cards now pass downwardly 75 through the feed rolls and close the card contacts 23, 24. The closure of the cam contacts 23 energizes control relay magnet 34 and closes relay points 35, thus providing a return circuit from 32 to 31 maintaining the 80 motor relay 29 energized at all times when cards are passing through the machine. Upon the passage of the last card, control relay 34 becomes deenergized thereby opening contacts 35 and causing the motor relay 90 29 to become deenergized upon the opening of contacts 33.

All of the above features are common and well known in present day tabulating machines and require no further description.

For the purposes of the present application I have illustrated the card circuit which is controlled by the perforated record cards in cooperation with brushes 13 and contact blocks 14, as controlling the magnets of an adding counter. However, the controlling magnets may be used for other purposes than adding. For example, they may be sorting or printing magnets or may be used for any desired purpose. The brushes 13 and contact blocks 14 constitute card controlled contacts for the magnet circuits and these parts will hereinafter be termed perforation reading devices.

The counter illustrated in Fig. 1 is of co.

ventional form such as is shown in Lake Patent No. 1,307,740. Actuation of the counter is controlled by the energization of magnets 40. In each counter there is provided a common bar 41 suitably connected to lines 42. Individual wires 43 connect the magnets 40 to the common bars 41 and also extend to plug sockets 44 on the usual tabulator plugboard. On this plugboard are other sockets 45 which, through cables 46, connect to the contact blocks 14. It will be understood that plug sockets 44 and 45 are connected by the usual plug connections. In the diagrammatic showing of the counter it is particularly noted that leads 43 contain neither resistances nor the usual relayless counter contacts heretofore used in connection with the counter circuits of the Lake patent heretofore mentioned. Such resistances and controlling contacts are entirely unnecessary in the present construction.

The means for supplying the magnets 40 with current for energizing same will now be described. Connected to line 28 is a wire 46 which connects to a controlling resistance 47, from the other end of which a suitable connection extends to line 31. Suitable adjustable taps 48, 49, are provided cooperating with the resistance 47 and by adjusting these taps in the manner of a potentiometer different current voltages may be secured on the circuit to which the taps are connected. This circuit extends from tap 49 through the card lever contacts 24, thence through an adjustable tap 50 cooperating with a ballast resistance 51. This resistance 51, if desired, may be of the iron wire type having a positive temperature coefficient. From resistance 51 a suitable lead connects to the primary coil 52 of a step-up mutual inductance device or transformer. The transformer comprises the usual core 53 and is provided with a secondary winding 54 in inductive relation to the primary 52. From primary winding 52 a wire 55 leads to fixed contact 56 of a timing device, interruptor or contactor. This timing device, interruptor or contactor may be of any desired form. As here shown it includes fixed contact 56 and movable contact 57, the latter being actuated to open the contacts by means of a cam 58 and resiliently closed. Connected across the movable and fixed contacts is a suitable condenser 59. The cam 58 is mounted upon the shaft 21 which, as previously described, is arranged to make one complete revolution per card cycle. This cam is provided with a number of low positions or dwells 60 (Fig. 2), which in number correspond with the number of index point perforations in each record card column. The arrangement and timing of the contactor and the relation of the transformer windings is such that just before any single perforation or plurality of perforations disposed in the row across the record

card come under the brushes, the primary circuit is closed. Immediately thereafter and before the brush or brushes have left the perforations in the record card this primary circuit will be interrupted. In this manner there will be a sudden cessation of direct current flow in the primary itself at the time the perforations are under the brushes. A corresponding sudden impulse of current flow of higher potential will be set up in the secondary winding 54. As shown in the diagram, this secondary winding 54 is disposed intermediate line 42 and a line 61 which connects with the common brush bar 62. Accordingly at the instant when the perforations of the given row are under the brushes current flow will occur in the brushes and magnet circuits. This current will be of sufficient intensity and voltage to rapidly energize the magnets 40 of all columns in which a perforation is under the brushes. In other columns the record card material will act as an insulator and interrupt the impulses in its particular magnet circuit.

The pulsating direct current impulses in the secondary circuit are exactly timed with the passage of index point perforations under the brushes. For a card having twelve index point perforation positions, for example, there will be twelve impulses in the secondary coil 54 for each card cycle and the magnets 40 will receive only such impulses as are permitted by the perforations in the record card. By properly proportioning the windings of the transformer and properly arranging the contactor and condenser 59 and adjusting taps 48, 49 and 50, it is possible to secure extremely rapid impulses in the magnet circuits so that these magnets will energize rapidly, attract their armatures and control the counter operation.

In practice it is found that a single contactor is effective to control a considerable number of magnet circuits. If desired, however, multiple contactors and multiple transformers may be utilized.

The supplementary card lever contacts 24 serve to interrupt the primary circuit when there are no cards in the machine and thus prevent the current flow across the brushes, when cards are absent. Inasmuch as the card and magnet circuits are normally deenergized it is not necessary to provide the usual controlling contacts heretofore employed to break the brush circuits in the interval between the cards. These contacts heretofore necessary may be entirely omitted.

What I claim is—

1. A card-controlled machine comprising in combination, a card controlled circuit, a circuit inductively coupled to said first mentioned circuit for energizing the same, a source of direct current for energizing said second mentioned circuit, and means for periodically varying the current in said sec-

- ond mentioned circuit in predetermined timed relationship with respect to the card control.
2. The combination set forth in claim 1 in which the first mentioned circuit is energized from the second mentioned circuit by a step-up mutual induction.
3. In a perforated record-controlled machine in combination with controlling magnets, perforation reading devices and circuits controlled thereby and including the said magnets and means for supplying a series of direct current impulses to said circuits, said impulses being timed to accord with the reading of the perforations by the reading devices, the said last mentioned means including a supply source of direct current, a transformer, and a contactor operated to make and break circuits to the said transformer in timed relation to the reading of the perforations by the reading devices whereby the transformer sets up direct current impulses in such of the aforesaid magnet circuits as are established by the corresponding reading devices.
4. In a perforated record-controlled machine, in combination with controlling magnets, means including brushes for connecting the said magnets in circuit by and through perforations in said records and means for supplying direct current impulses to said circuits each time the perforations in a record pass the said brushes, said last-mentioned means including a contactor driven at a given rate with relation to the movement of the cards and a transformer having a primary coil in circuit with said contactor and a secondary coil in circuit with said brushes in which the direct current impulses are induced.
5. In a perforated record-controlled machine, in combination with controlling magnets, perforation reading devices and circuits controlled thereby and including the said magnets, and means for supplying direct current impulses to said circuits and reading devices, said impulses being timed in accordance with the presence of perforations under the reading devices, said means including a secondary coil connected to the circuits and reading devices, and a primary coil inductively coupled to said secondary coil, and a source of direct current for energizing said primary coil.
- 55 6. In a perforated record-controlled ma-
- chine, in combination with controlling magnets, perforation reading devices and circuits controlled thereby and including the said magnets, and means for supplying direct current impulses to said circuits and reading devices, said impulses being timed in accordance with the presence of perforations under the reading devices, said means including a secondary coil connected to the circuits and reading devices, and a primary coil inductively coupled to said secondary coil, a source of direct current for energizing said primary and a circuit interruptor for interrupting the flow of current through the primary coil at the times when the magnet circuits are established through the record perforations.
7. In a perforated record-controlled machine having controlling magnets, circuits therefor and perforation reading means, in combination with means for inducing direct current impulses in said circuits at the times when they are established by the perforation reading devices, said last mentioned means including a timed contactor and interruptor in circuit with a direct current supply source, and a transformer having coils in circuit with the contactor and other coils connected to supply induced current to the perforation reading devices and the magnet circuits.
8. The invention set forth in claim 7 in which card lever contacts are provided in the interruptor circuit to close said circuit only when cards are passing through the machine.
9. The invention set forth in claim 7 in which a potentiometer connection in association with the direct current source of supply is provided for supplying current to the primary coil of the transformer and to the interruptor at the desired voltage.
10. The invention set forth in claim 7 in which a regulating resistance is provided in circuit with the coil of the transformer which is in circuit with the interruptor.
11. The invention set forth in claim 7 in which a resistance is provided in circuit with the primary transformer coil and in which means is provided for adjusting the amount of said resistance.

In testimony whereof I hereto affix my signature.

JAMES W. BRYCE.
